US00D598124S

(12) **United States Design Patent**
Py et al.

(10) **Patent No.:** US D598,124 S
(45) **Date of Patent:** ** Aug. 11, 2009

(54) **VIAL**

(75) Inventors: **Daniel Py**, Stamford, CT (US); **Norbert M. Assion**, Shelton, CT (US); **Julian V. Chan**, Spring Valley, NY (US); **Jacques Thilly**, Rixensart (BE); **Christian Vandecasserie**, Rixensart (BE)

(73) Assignee: **Medical Instill Technologies, Inc.**, Stamford, CT (US)

(**) Term: **14 Years**

(21) Appl. No.: **29/303,514**

(22) Filed: **Feb. 11, 2008**

(57) **CLAIM**

The ornamental design for a vial, as shown and described.

DESCRIPTION

FIG. 1 is a top perspective view of a first embodiment of a vial showing our new design;

FIG. 2 is a front elevational view of the vial of FIG. 1;

FIG. 3 is a side elevational view of the vial of FIG. 1;

FIG. 4 is another side elevational view of the vial of FIG. 1;

FIG. 5 is a top plan view of the vial of FIG. 1;

FIG. 6 is a rear elevational view of the vial of FIG. 1;

FIG. 7 is a bottom plan view of the vial of FIG. 1;

FIG. 8 is a top perspective view of a second embodiment of a vial showing our new design;

FIG. 9 is a front elevational view of the vial of FIG. 8;

FIG. 10 is a side elevational view of the vial of FIG. 8;

FIG. 11 is another side elevational view of the vial of FIG. 8;

FIG. 12 is a top plan view of the vial of FIG. 8;

FIG. 13 is a rear elevational view of the vial of FIG. 8; and,

FIG. 14 is a bottom plan view of the vial of FIG. 8.

The broken lines shown in the drawing figures are for illustrative purposes only and form no part of the claimed design.
